UNITED STATES PATENT OFFICE.

LAWRENCE E. CARLSON, OF HUNTINGTON, INDIANA.

ELECTRIC SWITCH.

1,352,246.

Specification of Letters Patent.

Patented Sept. 7, 1920.

Application filed November 20, 1919. Serial No. 339,485.

To all whom it may concern:

Be it known that I, LAWRENCE E. CARLSON, a citizen of the United States of America, residing at Huntington, in the county of Huntington and State of Indiana, have invented new and useful Improvements in Electric Switches, of which the following is a specification.

The object of the invention is to provide a simple and efficient means for use especially in connection with domestic electric lighting systems as a means of regulating or controlling the intensity of brilliance of the light, as for example in a sick room or where it is desired to maintain a light at all times, and yet wherein it is preferable to have the light tempered or materially reduced in intensity, to avoid the necessity as ordinarily practised of employing obstructing or semi-opaque shields for interfering with the distribution of the light to avoid the annoyance of the patient, or in other words to provide a means in connection with a house or similar lighting system whereby either the full intensity of the light or any proportion thereof may be utilized, and whereby the intensity thereof may be regulated momentarily by the attendant, to suit the conditions under which it is being used, and with this object in view the invention consists in a construction and combination of parts of which a preferred embodiment is shown in the accompanying drawing, wherein:

Figure 1 is a rear view of the switch, a portion of the casing being broken away. Fig. 2 is a longitudinal sectional view of the same.

Fig. 3 is a front view.

Fig. 4 is a detail view of the rheostat or resistance bar.

The invention is shown in connection with an ordinary house lighting switch of the on and off type employing the push buttons 10 and 11, a pivotal switch closer 12 and the contacts 13 and 14, the contact 13 as usual forming the terminal of a circuit wire 15. The other circuit wire 16, instead of

being extended as in the ordinary practice directly to the contact or terminal 14 is arranged to include a rheostat 17 which may be mounted upon the same base plate 18 as the switch mechanism and consists of a blade 19 pivotally mounted as at 20 and designed to traverse a rheostat or resistance bar 21 of carbon or the like made in segmental form as indicated, the circuit wire 16 being connected with the hub of the blade 19 while the intermediate connecting wire 16' extending to the contact or terminal 14 is attached to one end of said resistance or rheostat bar 21 as shown at 22.

Obviously by varying the position of the blade 19 with relation to the resistance bar, by turning the knob 23 which is exposed at the front surface of the base plate 18 and hence is as accessible to the operator as the buttons 10 and 11, the current may be caused to traverse either a greater or a less resistance and thus be modified in intensity accordingly, to the end that when desired a very dim light may be produced at the lamps, or the full strength of the current may be utilized as preferred, and in variation between these extremities may be secured merely by the manipulation of said knob.

What is claimed is:

A switch mechanism for lighting systems embodying a base plate, a circuit closer, provided with terminals and a switch arm for connecting the same and means operable from the front of the base plate for actuating the switch arm, an arcuate resistance bar mounted on the base plate and terminally connected with one of said contacts, a blade pivotally mounted at one end of the base plate and having its remaining end bearing upon the resistance bar for movement thereof, and a knob exposed at the front of the base plate and connected to the pivot of the blade, whereby angular movement may be imparted to the latter for the purpose specified.

In testimony whereof I affix my signature,

LAWRENCE E. CARLSON.
